A. B. HENDRICKS, JR.

TRANSFORMER

Filed Nov. 10, 1921

Inventor:

Allan B. Hendricks Jr.

UNITED STATES PATENT OFFICE.

ALLAN B. HENDRICKS, JR., OF PITTSFIELD, MASSACHUSETTS, ASSIGNOR TO GENERAL ELECTRIC COMPANY, A CORPORATION OF NEW YORK.

TRANSFORMER.

Application filed November 10, 1921. Serial No. 514,328.

To all whom it may concern:

Be it known that I, ALLAN B. HENDRICKS, Jr., a citizen of the United States, residing at Pittsfield, county of Berkshire, State of Massachusetts, have invented certain new and useful Improvements in Transformers, of which the following is a specification.

My invention relates to electrical transformers. For some purposes, a source of current at very high potential is desirable, this being especially true in connection with the testing of high tension insulators, the investigation of corona effects on high tension transmission lines and various other theoretical investigations. The present invention therefore relates more particularly to transformers adapted to be used under circumstances requiring the production of current at very high potentials.

A single transformer designed to deliver current at very high potential is expensive and bulky because of the large amount of insulation necessary and the considerable spacing and consequent large amounts of other material required because of the high potential differences at which various parts of the transformer must be operated. It has been suggested that this difficulty be overcome by the use of a plurality of transformer units with their high tension terminals connected in series, each unit being separately excited and all except the first one being insulated from the primary source of current and from ground by one or more insulating transformers. This method is objectionable because of the expense and the inconvenience of handling the large number of units. Another method suggested has been the use of a plurality of auto-transformers connected in series, but the very high reactance of such a system makes it of little value for most purposes.

The main object of the present invention is to overcome the disadvantages of the arrangements which have heretofore been suggested by the use of a plurality of transformer units connected in series, the first unit being preferably excited directly from some suitable source of current and each of the higher units being excited by means of exciting windings which are structurally combined with the next unit below but which operate independently of the main windings of the transformer unit with which they are structurally associated. Another object of

the invention is to provide means for protecting the windings from destructive effects due to high frequency oscillations caused by disturbances in the circuit from the breakdown of insulation under test, sudden short circuits, or other sudden changes in circuit conditions.

Other objects and advantages will appear from the following description taken in connection with the accompanying drawing, in which Fig. 1 indicates the construction and arrangement of parts where two transformer units are used in accordance with the present invention, a portion of each unit being broken away to reveal the arrangement and connections of the windings and the means already referred to for protecting them against high frequency oscillations, and Fig. 2 is a diagram of the arrangement of the windings and their connections in the two units.

Like reference characters refer to similar parts in both figures of the drawing.

In the embodiment of the invention revealed in the drawing, the system comprises two transformer units 1 and 2 so connected that the terminal voltage of the system will equal the vector sum of the individual voltages of the two units. It will become apparent as the description proceeds that the reactance of such a system is very low as compared, for instance, with the reactance of an auto-transformer system, and that therefore the terminal voltage of two units connected in series is substantially equal to the arithmetical sum of the individual voltages of the units. It will further be apparent that additional units may be added in order to develop greater terminal voltage until the number of units is such that their combined reactance causes the vector sum of the individual voltages to differ so much from the arithmetical sum as to become objectionable.

The units are preferably all similar so that they may be used interchangeably and a description of the first unit will therefore indicate the construction of each succeeding one. As in each of the other units, the first one includes a casing 3 surrounding the transformer proper which is preferably immersed in an insulating and cooling fluid such as oil. The transformer has a core with a central leg 4 upon which is a main low voltage primary winding 5 and a main

high voltage winding 6. These two windings have their lower ends connected by a conductor 7 which is connected to the casing 3. The upper end of the low voltage winding 5 of the first unit is connected by a conductor 8 to one terminal of the source of current 9 and the casing 3 of this first unit is connected to the other terminal of the source of current by a conductor 10, so that this low voltage winding is adapted to be excited directly by the source of current.

Upon the leg 4 of the core, there is also wound a primary winding 11 and a secondary winding 12. These may be called exciting windings as their purpose in each unit is to furnish current for exciting the main primary and the primary exciting winding of the next unit above. The primary exciting winding 11 is connected in parallel with the main primary winding 5 and each of these windings has the same number of turns as they are both wound upon the same core and have the same potential applied across their terminals. The secondary exciting winding 12 may have the same number of turns as its primary because these windings are merely used to excite the main primary winding of the next unit above and not to produce any increase in potential in themselves.

While the main secondary winding 6 is designed to develop very high potential, possibly as great as two hundred thousand volts or more, between its terminals, the potential difference between the terminals of each of the three windings 5, 11 and 12 is comparatively low, perhaps something like a thousand volts. The secondary exciting winding 12 therefore has its turns concentrated near the upper end of the main high voltage winding 6 since it must be insulated therefrom at its lower end. The turns of the primary exciting winding 11 are also concentrated near the upper end of the main windings 5 and 6 and under the secondary exciting winding 12 so that the two exciting windings 11 and 12 may be in good inductive relation to each other. The lower end of the secondary exciting winding 12 and the upper end of the main secondary winding 6 are both connected to a conductive protective shield 16 which will be described later. The potential of all parts of the winding 12 is therefore far above that of the lower end of the main secondary winding. All parts of the primary exciting winding 11 however are at very much lower potential as this winding is in parallel connection with the main low voltage winding 5. The windings 5 and 11 are therefore well insulated from the windings 6 and 12 by a suitable insulating barrier 13.

The upper or high voltage terminal of the main secondary winding 6 is connected to a

tubular conductor 14 supported in a suitable insulator 15 and extended into conductive connection with the casing 3 of the next unit above. This upper terminal of the winding 6 and also the lower end of the secondary exciting winding 12 are connected to the conductive protective shield 16. The upper end of the secondary exciting winding 12 is connected by an insulated conductor 16 carried inside the tubular conductor 14 to the upper ends of both the main primary winding 5 and the primary exciting winding 11 of the next unit above. It will be obvious that with the connections which have been described, the secondary exciting winding 12 of each unit is connected across the terminals of both the main primary winding 5 and the primary exciting winding 11 of the next unit above so as to furnish exciting current for these two windings. These two windings 5 and 11 in each unit induce current in their respective secondary windings 6 and 12. The purpose of connecting the lower end of the secondary exciting winding 12 to the protective shield 16 and thence through the tubular conductor 14 and the casing 3 of the next unit to the lower ends of the two primary windings 5 and 11 of this next unit is to avoid the use of a separate conductor between these points. It is obvious that such a separate conductor may be used if desired, in which case the connection 7 between the lower ends of the primary windings 5 and 11 and the lower end of the main secondary winding 6 may be omitted.

The transformer units have been described as being similar in construction and arrangement of parts but they may be connected together in a variety of different ways. As shown in Fig. 1 of the drawing, the casing 3 of the first unit is connected to the ground 17, this connection also serving to complete a path to ground from the lower end of the main or high tension secondary winding 6 of this first unit. There is therefore a continuous series path from the ground 17 through the main secondary winding 6 and tubular conductor 14 of the first unit, and the casing 3, main secondary winding 6 and tubular conductor 14 of the second unit to the high voltage terminal 18 of the system. The total potential difference between the upper terminal of the system and its lower terminal or ground will be the vector sum of the potentials generated in the high tension windings of the individual units and it is obvious that an extremely high terminal voltage may be attained by the use of additional units, its practical maximum limit being determined only by the combined reactances of the individual units as already explained and by the insulation provided between the higher units and ground. As indicated in Fig. 1 of the drawing, the casing of the lower unit is

grounded and does not need to be insulated from the ground. The casing of the second unit, however, is at a potential equal to that of the upper high tension terminal of the 5 lower unit and must be correspondingly insulated from ground as by mounting it upon an insulating stand 19. The casing of each unit must be insulated from ground for a potential difference equal to the combined potential of the other units between this one 10 and the ground terminal of the system.

It will be apparent that in the last unit of the system, the primary and secondary exciting windings 11 and 12 are idle as their only 15 purpose is to excite an additional unit in case one may be found desirable at any time. It will also be apparent that these two exciting windings operate entirely independently of the main transformer windings 5 20 and 6, and are associated with them on the same core merely for purposes of economy in construction and not to create any transfer of energy between the two sets of windings.

25 During the operation of a high tension system such as has been described, there frequently occur sudden disturbances in the high tension circuit due to such causes as sudden short circuits, and the breakdown of 30 insulating material which is being subjected to high potential tests. As is well known to those familiar with electrical phenomena, such a disturbance in the exterior testing circuit may cause an oscillating current of very 35 high frequency and at potentials far in excess of the normal potential at which the system is designed to operate to enter the upper unit at its terminal. As this high frequency current reaches the end turns of the high 40 tension winding, it may produce excessively high potentials between the turns because of their inductance.

45 The protective shield 16 is therefore provided between the winding 12 and the upper turns of the winding 6. This shield is in the form of a cylindrical member composed of conductive material. It is of considerable depth or width at that portion of the windings directly under the connection between 50 the high tension winding and the high tension terminal as the greatest protection is obviously necessary at this point. The depth or width of the shield decreases in each direction from this point along the turns of 55 the winding and therefore away from the point at which destructive high frequency oscillating disturbances may enter the windings. The shield is split at the side opposite this point in order that it may not form a 60 short circuited conductor to interfere by its reactance with the flow of magnetic flux in the core. Without this shield, the closely wound turns of the windings act as condenser plates and there is also a considerable 65 capacity outwardly between these turns and

the transformer casing and also inwardly between these turns and the transformer core. A high frequency high tension current coming in through the terminal would penetrate the turns through these condenser paths, and as some current would leave each turn through the lateral paths, it is obvious that the currents in the upper turns would be very high and would cause the potentials 70 between the first few turns to reach such excessive values as to cause serious injury to the winding. This injurious effect is prevented, however, by the shield which has been described. The shield is instantly brought to the potential of any dangerous oscillating 80 current which may come in through the terminal and immediately charges the turns of the winding opposite the shield to its own potential by electrostatic induction, thus preventing flow of current through the capacity 85 of the turns and consequently preventing any excessive differences of potential between these turns. This electrostatic effect decreases gradually with the distance from the terminal so that there may be no abrupt 90 change in the effect on the turns at its lower edge, this gradual decrease being due to the varying depth of the shield. In securing this gradual decrease in the electrostatic effect, it is preferred for structural reasons to 95 vary the depth of the shield as shown rather than to vary its distance from the turns.

What I claim as new and desire to secure by Letters Patent of the United States, is,—

1. In a transformer, a magnetic core, main primary and secondary windings surrounding the core, a second secondary winding surrounding the core, and a second primary winding in good inductive relationship with the second secondary winding, the 100 turns of the second secondary end of the second primary windings being concentrated 105 near one end of the main secondary winding.

2. In a transformer, a magnetic core, main primary and secondary windings surrounding the core, a second secondary winding surrounding the core with its turns concentrated near one end of the main secondary winding, and a second primary winding with its turns concentrated near one end of 110 the main primary winding and in good inductive relationship with the second secondary winding.

3. In a transformer, a magnetic core, main primary and secondary windings surrounding the core, a second secondary winding surrounding the core, a second primary winding surrounding the core, the second secondary and primary windings being between the main secondary and primary windings, and a conductive shield between the two secondary windings and connected to the high tension end of the main secondary winding.

4. In a transformer, a magnetic core, main 130

primary and secondary windings surrounding the core, a second secondary winding surrounding the core, a second primary winding surrounding the core, the second 5 secondary and primary windings being between the main secondary and primary windings, and a conductive shield between the two secondary windings and connected to the high tension end of the main 10 secondary winding, said shield varying in width along the main secondary winding.

5. In a transformer, a magnetic core, a primary and a secondary winding surrounding the core, and a conductive shield between 15 said two windings and connected directly to the high tension end of the secondary winding.

6. In a transformer, a magnetic core, a primary and a secondary winding surrounding the core, and a conductive shield between 20 said two windings and connected directly to the high tension end of the secondary winding, said shield varying in width along the secondary winding.

25 7. In a transformer system comprising two transformer units, a magnetic core in each unit, main primary and secondary windings surrounding each core, a second secondary winding and a second primary winding surrounding each core, the two 30 primary windings in the second unit being connected in parallel and across the second

secondary winding of the first unit, and means for exciting the two primary windings of the first unit. 35

8. In a transformer system comprising two transformer units, a magnetic core in each unit, main primary and secondary windings surrounding each core, a second secondary winding and a second primary 40 winding surrounding each core, the second secondary and the second primary winding in each unit being concentrated near one end of the main secondary winding in the same unit, the two primary windings in the 45 second unit being connected in parallel and across the second secondary winding of the first unit, and means for exciting the two primary windings of the first unit.

9. In a transformer system comprising a 50 plurality of transformer units, a magnetic core in each unit, and main primary and secondary windings surrounding each core, said secondary windings being connected in series, at least one of said cores having a 55 second secondary winding and a second primary winding concentrated near one end of its main secondary winding, each of said second secondary windings being connected to supply primary exciting current to an 60 adjacent unit.

In witness whereof, I have hereunto set my hand this 8th day of Nov., 1921.

ALLAN B. HENDRICKS, JR.

Certificate of Correction.

It is hereby certified that in Letters Patent No. 1,567,844, granted December 29, 1925, upon the application of Allan B. Hendricks, jr., of Pittsfield, Massachusetts, for an improvement in "Transformers," an error appears in the printed specification requiring correction as follows: Page 3, line 106, claim 1, for the word "end" read *and*; and that the said Letters Patent should be read with this correction therein that the same may conform to the record of the case in the Patent Office.

Signed and sealed this 15th day of June, A. D. 1926.

[SEAL.]

M. J. MOORE,
Acting Commissioner of Patents.
